UNITED STATES PATENT OFFICE.

FRANK WIBERLEY, OF JAMAICA, NEW YORK, ASSIGNOR TO BARTHELS MANUFACTURING CO., OF GLENDALE STATION, NEW YORK, N. Y., A CORPORATION OF NEW YORK.

TIP FOR LACINGS.

1,099,479.

Specification of Letters Patent.

Patented June 9, 1914.

Application filed March 7, 1912. Serial No. 682,300.

To all whom it may concern:

Be it known that I, FRANK WIBERLEY, a citizen of the United States, and resident of Jamaica, Long Island, county of Queens, State of New York, have invented certain new and useful Improvements in Tips for Lacings.

My invention relates to tips for lacings and has for its object to provide a tip of this description which may be securely fastened against removal from the lacing and which will improve the appearance and facilitate the insertion of the lacing through eyelets.

My invention further contemplates a simple method for making said tips and applying them to said lacings.

My invention will be fully described hereinafter and the features of novelty will be pointed out in the appended claim.

Reference is to be had to the accompanying drawings in which—

Figure 1 is a face view of a tip before having been applied to the lacing; Fig. 2 is an elevation showing the tip applied to the lace; Fig. 3 is a longitudinal section thereof on the line 3—3 of Fig. 1; Fig. 4 is a cross section thereof on an enlarged scale on the line 4—4 of Fig. 2; and Figs. 5 and 6 are elevations of other forms of my invention.

In the form of my invention shown in Figs. 1 to 4 inclusive of the drawings the tip comprises the preferably cylindrical body A formed of sheet material bent about the end of the lacing B and preferably having its longitudinal edges overlapping as shown best in Fig. 4. The body A is provided with inwardly projecting parallel projections C which in the finished tip extend completely about the said body in a circumferential direction and serve to firmly and securely grip the lacing B to prevent the removal of the tip therefrom. In making this type of tip, I first take a sheet of metal or any other suitable material of any convenient dimensions and corrugate or crimp the said sheet through the medium of any suitable means to produce the projections C. This corrugated or crimped sheet of material is then cut into sections such as shown in Fig. 1 and having the proportions necessary to produce the desired length of tip and to properly surround the lacing. These corrugated or crimped sections are

then bent about the ends of the lacings in a direction parallel with the corrugations in any convenient manner and are then placed between pressure jaws or dies having corrugated or crimped surfaces corresponding to the corrugations or crimpings of the sections and adapted to register therewith. Power is applied in any desired way to the jaws or dies to actuate them to firmly compress the tip and consequently the projections C relatively to the lacings B. The action of the jaws or dies is preferably such as to reduce the diameter of the tip as pressure is applied this being made possible by having the longitudinal edges of the tip overlap. The consequence of this operation is that the lacing will be firmly gripped by the entire inner periphery of each projection C and securely held in place thereby. That is all points along the entire said inner periphery of each projection will exert a pressure toward a substantially common central point so that dislocation of the tip accidental or otherwise relatively to the lacing is practically impossible.

In the form of my invention illustrated in Fig. 5 the tip comprises a body having inwardly projecting parallel projections C' similar to the projections C but located preferably only at the inner portion of the said body. The remainder of the body comprises smooth portion A' which is preferably tapered toward the outer or free end of the body to facilitate the insertion of the tip and lacing into and through the customary eyelets. In this form of tip the corrugated portion is tightly rolled about the end of the lacing which is thus firmly gripped by the projections C', so that the smooth portion A' extends beyond the end of the lacing and is tightly rolled into conical form. The form of tip shown in Fig. 6 is similar to that illustrated in Fig. 5 excepting that the preferably tapered free end portion instead of being smooth as shown at A' is provided with corrugations A² extending longitudinally or lengthwise thereof. In producing these two latter forms of tip I also take a sheet of suitable material and partly corrugate or crimp it at spaced intervals by any suitable means to produce the projections C' and smooth portion A' or corrugated portion A². After this has been done the said sheet is cut into sections in the same manner as in the form shown in Figs. 1 to 110

4 inclusive and the sections are similarly bent about the ends of the lacings B, and compressed thereon by means of suitable jaws or dies having properly formed faces 5 to produce the smooth or corrugated and if desired tapered end A' or A² and to register with the corrugation which form the projections C', in exactly the same way as hereinbefore described with respect to the 10 first form of my invention. These latter forms of tip are thus also firmly secured to the lacing against accidental or other removal and in addition are provided with the smooth or corrugated and preferably tapering end which makes it a simple matter to insert the tip and lacing into and through the customary eyelets.

By corrugating or crimping the material while in a flat condition and in sheet form 20 and then cutting it into the desired dimensions a maximum number of tips may be produced from a given sheet and the cost of production of said tips is greatly reduced. The tips produced in this way are also of a 25 relatively small diameter compared with existing structures and have a much neater appearance than tips which are crimped after they have been put on the laces. Instead of first corrugating the material and then cut-

ting it into sections the corrugating and cutting may be done simultaneously in any suitable manner. 30

It is to be understood that my improved tips may be made of any material suitable for the purpose. 35

Various changes in the specific forms shown and described may be made within the scope of the claim without departing from the spirit of my invention. 40

I claim:

The combination of a lacing and a tip therefor, said tip being formed of a sheet of corrugated material, said corrugated material being tightly rolled and compressed about the end of said lacing to grip the same, and 45 said sheet of material having its longitudinal edges overlapping and the corrugations thereof interlocking with each other and thereby extending continuously circumferentially of the tip whereby a tip of extremely small diameter is secured. 50

In testimony whereof I have hereunto set my hand in the presence of two subscribing witnesses.

FRANK WIBERLEY.
